DENTAL DEVICE FOR OBTAINING THE CENTRIC
RELATION OF THE JAWS
Grover C. Reynolds, 4401 Charlotte Ave.,
Nashville, Tenn.
Filed Jan. 22, 1962, Ser. No. 167,623
7 Claims. (Cl. 32—19)

This invention relates to a dental device for obtaining the centric relation of the jaws, and more particularly to such a device which may be universally adjustable.

In the conventional method of making a set of false teeth for a patient, impressions of the person's gums are made in soft plastic material such as wax. A harder stone-like material in molten form is poured into the molds of the gums formed by the impressions and permitted to set to form a stone-like reproduction or model of the edentulous gums. Another pink plastic material, such as wax, is pressed over the gum surfaces of the stone-like models for both the upper and the lower jaws to form upper and lower base plates. A flat metal supporting plate is then placed against the outer surface of each base plate opposite the gum surface in such a manner that the metal plates oppose each other in spaced relation. The upper metal plate has a depending stylus, while the lower metal plate has a thin layer of wax spread over a small surface directly beneath the stylus.

The plastic base plates and the supporting metal plates are removed from their respective models and inserted into the mouth of the patient and the gums inserted into the cavities or impressions of the plastic base plates. The patient closes his mouth and chews, moving his lower jaw laterally and back and fourth to permit the stylus to trace a configuration in the waxed surface on the lower metal plate. In all patients, the stylus describes a substantially V-shaped path, known as a "Gothic Arch."

The plastic base plates and the metal plates are then removed from the patient's mouth and the models are replaced in the impressions of the base plates. With the stylus held in the apex of the "Gothic Arch" and adjusted to proper elevation, the models are secured to an articulator by means of plaster of Paris.

In this crude manner, the centric relation of the jaws and gums are obtained preliminary to the making of a set of false teeth for the patient. The term "centric relation" refers to the natural relationship of an upper jaw and a lower jaw of a patient when the jaws are normally closed. By nature, the centric relation of any person's jaws is not symmetrical, nor is it identical to the centric relation of any other person's jaws.

It is therefore an object of this invention to provide a pair of support plates for plastic dental base plates, which support plates may be universally adjusted with respect to each other, while in the patient's mouth, and locked in the adjusted position of the plates in order to obtain the true centric relation of the patient's jaws.

Another object of this invention is to provide a pair of support plates for obtaining the centric relation of the jaws, one plate having a plurality of styli, for not only establishing the "Gothic Arch," but also for orienting the plates in centric relation.

Another object of this invention is to provide a dental device for obtaining the centric relation of the jaws, which is simple and economical in structure, and which may be easily and quickly manipulated in not only obtaining the centric relation of the jaws, but also transferring this relationship to the articulator.

Further objects and advantages of the invention will be apparent from the following description taken in conjunction with the drawings, wherein:

FIG. 1 is a front elevational view of the invention, mounted on an articulator in closed position;

2

FIG. 2 is a side elevation of the invention disclosed in FIG. 1;

FIG. 3 is a top plan view of the lower support plate;
FIG. 4 is a bottom plan view of the upper support plate;

5 and
FIG. 5 is a section taken along the line 5—5 of FIG. 3.
Referring now to the drawings in more detail, and particularly to FIGS. 1 and 2, the upper plastic base plate or bite plate 10, having a surface coating of soft wax 11, is formed around a stone-like model 12 of the upper gum of the patient, and secured to the upper surface of the upper flat metal support plate 13. The upper plate 13 is provided with laterally extending arms 14 having apertures 15 therethrough, so that the arms 14 may be immersed in the soft wax 11 to sustain the upper support plate 13 upon the bite plate 10. The apertures 15 permit the soft wax to seep through the arms 14 to provide a more secure bond. To assist in accomplishing the same purpose, the periphery of the upper plate 13 is provided with serrations 16.

10 In a like manner, a lower plastic base plate 19 coated with wax 20, and forming an impression of the lower gum on the lower stone-like model 21, is secured to a lower flat metal support plate 22 by means of laterally extending arms 23 having apertures 24, and serrations 25.

15 A T-shaped bracket 28 is secured to the bottom surface of the upper support plate 13 by any convenient means, such as the bolts 29. Slidably mounted through aligned apertures in the upper plate 13 and the bracket 28 are three styli 30, 31 and 32, arranged to slidably reciprocate axially and substantially normal to the upper plate 13. The bracket 28 and the upper plate 13 provide bearings for the axial movement of the styli 30, 31 and 32. The top of each stylus, 30, 31 and 32, terminates in an enlarged head 33 which is connected to a coil spring 34 surrounding the upper portion of each stylus 30—32 between the head 33 and the top of the upper plate 13. The springs 34 are adapted to bias the styli 30—32 downward through the upper plate 13.

20 Threaded laterally through the forward edges of the bracket 28 are adjustable set screws 35, 36 and 37, each adapted to lockingly engage a corresponding stylus 30—32 in any axially adjusted position. The axes of the set screws 35—37 are substantially normal to the axes of the styli 30—32.

25 The openings 39 (and aligning openings in the plate 13) may be provided in the bracket 28 to receive the styli 30—32 for a patient who has a small or narrow mouth.

30 A pair of pivotal posts 41 and 42 extend upwardly from the top of the lower support plate 22 to provide journals for the ends of the three locating arms 43, 44 and 45. The arms 43—45 are arcuate, being curved from their journaled ends inwardly toward the center of the plate 22. Each of the arms 43—45 is provided, adjacent 35 the inner surfaces of their free ends, with a plurality of notches, grooves or serrations 47, as best disclosed in FIG. 3. FIG. 3 also discloses the location of the three styli 30, 31 and 32, when they have engaged the top surface of the bottom plate 22 in an adjusted position for a patient. Although the arms 44 and 45 are substantially the same length, the arm 43 is somewhat shorter, since it only has to extend from its journaled end to engage the front stylus 30. Even though the arms 43 and 44 are journaled about the same post 41, and the arm 45 is journaled about a separate post 42, the means of journaling these arms to the plate 22 is not of particular importance, so long as the arms are mounted to carry out their intended function. The arms 43—45 must be of sufficient length that the serrated edge of each of them 40 will engage their corresponding styli 30—32 for any adjusted position of a patient's jaws.

45 Located on the upper surface of the lower support plate

22 and adapted to register with the lower pointed end of the stylus 30 is a layer of wax 50. When the plates 13 and 22 are in operative position and the jaws of the patient are closed, the movement of the jaw will cause the stylus 30 to form a "Gothic Arch" 51 in the wax 50.

The operation of the invention is as follows:

After the models of the gums 12 and 21 have been poured and set, and the impressions removed, a plastic material is heated and pressed over the gum surfaces of the models 12 and 21 to form the plastic base or bite plates 10 and 19. After the bite plates 10 and 19 have hardened, coatings of soft wax 11 and 20 are placed on the outer opposing surfaces of the respective bite plates which are placed in the patient's mouth. The upper plate 13 and the lower plate 22 are then assembled together with the styli 31 and 32 locked in raised position, and only the stylus 30 unlocked to engage the lower support plate 22. In this assembled position, the arms 43-45 remain disengaged from their respective styli 30-32. The support plates 13 and 22 are held together by wire tongs of any convenient construction and inserted into the patient's mouth. The plates 13 and 22 are generally centered in the mouth so that the soft wax 11 and 20 will infiltrate the apertures 15 and 24 and mesh with the serrations 16 and 25 of the respective plates. After the upper plate 13 has become thus secured to the base plate 10, and the lower support plate 22 secured to the lower base plate 19, the tongs are removed.

When the mouth, lips and jaws of the patient are in proper vertical relation, the set screw 35 is tightened to lock the front stylus 30 to the upper plate 13, so that the pointed end of the stylus 30 penetrates the wax 50 and touches the upper surface of the lower support plate 22. The patient is then requested to chew so that the stylus 30 will form the "Gothic Arch" 51 in the wax 50. When the patient stops chewing, the stylus 30 is located in the apex of the "Gothic Arch" 51 with the pointed ends of the styli 31 and 32 resting on the upper surface of the lower support plate 22. The set screws 36 and 37 are tightened to lock the styli 31 and 32 in these positions, and the arms 43, 44 and 45 are manually pivoted inwardly about their respective posts 41 and 42 until the corresponding notches 47 engage the respective styli 30-32.

The threaded posts 41 and 42 are adapted to pass through and hold their respective arms 43-45 in pivotal or locked positions by means of nuts, as disclosed in FIG. 5. After the arms 43-45 engage their respective styli 30-32, they may be locked by tightening the posts 41 and 42 in their respective nuts. Since this tightening must be done while the plates 13 and 22 are in the mouth, it would be preferable for the posts 41 and 42 to slant forward to make the heads of the posts more accessible to a screwdriver. The arms 43-45 and plate 22 may be bent at the proper places to provide for the slanting posts.

Each plate 13 and 22, together with its attached bite plate 10 and 19 respectively, is then removed from the patient's mouth, either separately or together. The bite plates 10 and 19 are then fitted over their respective gum models 12 and 21. The pointed ends of the styli 30-32 are then reinserted in the same notches 47 of their respective arms 43-45 which they occupied when in the patient's mouth. By inserting the pointed end of the stylus 30 back into the apex of the "Gothic Arch" 51, the three styli will automatically fit into the same notches 47 which they occupied in the patient's mouth. The models 12 and 21 are then attached to a conventional articulator 55 by means of plaster of Paris 56 and 57.

By this means, the jaws and gums of the patient are properly simulated in true centric relation, and by removing the entire plate assembly and the base plates 10 and 19, the artificial teeth may be made on the gum models 12 and 19 for the patient in true centric relation.

It will be noted that the upper and lower support plates 13 and 22 afford complete universal adjustment. In the first place, the plates 13 and 22 are separated from each other, and in the second place, the three styli 30, 31 and 32 are arranged in a triangular pattern, each stylus being axially adjustable with respect to the upper support plate 13. Thus, the upper plate 13 is permitted to tilt in practically any direction and about any axis with respect to the lower plate 22. The axially slideable styli 30-32 also provide relative vertical adjustment of the spacing between the plates 13 and 22. The lateral adjustments of the plates 13 and 22, that is, from side to side and also backward and forward, are made by generally centering the plates 13 and 22 when they are initially placed in the patient's mouth. Moreover, the lower plate 22 is sufficiently large to permit the styli 30-31 to contact the plate 22 in various lateral positions.

It will be apparent to those skilled in the art that various changes may be made in the invention, without departing from the spirit and scope thereof, and therefore the invention is not limited by that which is shown in the drawings and described in the specification, but only as indicated in the appended claims.

What is claimed is:

1. A dental device for obtaining the centric relation of jaws comprising:

- (a) a first plate for receiving an impression of one of the gums of the jaws,
- (b) a second plate for receiving an impression of the other gum,
- (c) three styli,
- (d) means on said first plate mounting said styli in a spaced apart triangular pattern normal to said first plate for axial reciprocation therethrough,
- (e) means on said first plate for locking each stylus in an adjusted axial position,
- (f) means mounted on said second plate movable toward engagement with each of said depending styli for locating the laterally adjusted positions of said styli relative to said second plate when said plates are assembled and the jaws are closed.

2. The invention according to claim 1 in which said locating means comprises an arm for each stylus, each arm having a plurality of notches, and means permitting movement of each arm toward and away from its corresponding stylus so that each notch will engage said stylus at a different laterally adjusted position.

3. The invention according to claim 2 in which each arm is arcuate and has one end pivoted to said second plate, so that each arm will swing across said second plate.

4. The invention according to claim 1 in which apertured arms are mounted on each plate for immersion in soft wax adhering to the bite plates of the dental device.

5. A dental device for obtaining the centric relation of the jaws comprising:

- (a) an upper plate for receiving an impression of the upper gum, and having a longitudinal axis extending from front to back,
- (b) a lower plate for receiving an impression of the lower gum and adapted to oppose said upper plate when said plates are assembled,
- (c) first, second and third styli,
- (d) means on said upper plate for mounting said styli normal to said upper plate for axial reciprocation therethrough,
- (e) said first stylus being mounted on said longitudinal axis, and said second and third styli being located substantially equidistant on opposite sides of the longitudinal axis, and behind said first stylus,
- (f) means on said upper plate for locking each stylus in an adjusted depending axial position, and
- (g) means mounted on said lower plate movable toward and away from each stylus to engage and lat-

erally locate each corresponding stylus relative to said lower plate when said plates are assembled.

6. The invention according to claim 5 in which a coil spring for each stylus is mounted on said upper plate to independently bias each stylus toward said lower plate when said plates are assembled.

7. The invention according to claim 5 in which the means for locking each stylus comprises a set screw mov-

ably mounted adjacent each stylus for engagement and disengagement therewith.
